OILER

Oscar H. Jung and Paul E. Heffelfinger,
Milwaukee, Wis.

Application March 2, 1936, Serial No. 66,684

4 Claims. (Cl. 184—54)

This invention appertains to oilers of the type particularly adapted for lubricating the bearings of shafts.

One of the primary objects of our invention is to provide a visible oiler for shafts which will supply oil to the bearing in direct accord with the needs of the bearing without waste and without any attention on the part of the operator other than to fill the reservoir from time to time.

Another salient object of our invention is to provide a lubricator embodying an interior thermo-dome affected by the heat of the bearing for supplying oil thereto in accordance with the temperature of the bearing.

A further object of our invention is to provide novel means for arranging the thermo-dome in the lubricator or oiler, whereby the same will not be affected by outside temperature, but by the temperature of the bearing alone, the dome being positioned within the reservoir so that the oil surrounding the dome will function as a heat insulator from outside temperature.

A further important object of our invention is the provision of novel and simple means for restricting the flow of oil from the reservoir, so that the oil will be delivered a drop at a time to the bearing.

A still further object of our invention is to provide an improved shaft oiler of the above character, which will be durable and efficient in use, one that will be simple and easy to manufacture, and one which can be placed upon the market and incorporated with a bearing at a small cost.

With these and other objects in view, the invention consists in the novel constructions, arrangement, and formation of parts, as will be hereinafter more specifically described, claimed, and illustrated in the accompanying drawing, in which drawing:

Figure 1 is a side elevation of our improved oiler, with parts thereof broken away and in section to illustrate structural details, the view being shown on an enlarged scale with the oiler associated with a fragment of a bearing.

Figure 2 is a side elevation of an adapter for facilitating the association of the oiler with certain types of bearings.

Figure 3 is an enlarged, fragmentary, detail sectional view illustrating the means of forming the guide sleeve for the oil limiting plug.

Referring to the drawing in detail, wherein similar reference characters designate corresponding parts throughout the several views, the letter O generally indicates my improved oiler

or shaft lubricator, which comprises a reservoir 5. This reservoir can be constructed from any desired material, but preferably of glass, so that the height of the oil therein can be readily seen by an observer.

In the present instance, the reservoir 5 is in the nature of a bottle and hence includes a body portion 6 having a restricted neck 7. This neck 7 is closed by a cap 8, which can be detachably united therewith in any conventional manner. As illustrated, the cap and neck are provided with mating threads. A gasket or washer 9 is associated with the cap for engaging the outer edge of the neck so as to seal the reservoir.

In accordance with our invention, the cap 8 is provided with an opening 10 in which is inserted the feed tube 11. The feed tube 11 has formed thereon an annular collar 12 for engaging the outer face of the cap and for limiting the insertion of the feed tube within the cap. The extreme inner end of the feed tube is upset or flanged over, as at 13, into intimate contact with the interior of the cap. This construction rigidly and permanently secures the feed tube to the cap. The outer end of the feed tube may be provided with exterior threads 14, for a purpose which will be later set forth.

It is highly desirable to limit the flow of oil from the reservoir to a bearing, so that the oil will be fed only a drop at a time. This can be accomplished in different manners, such as by forming the outer end of the tube with a minute opening. This, however, is expensive, and hence we have provided a novel and simple means for restricting the oil flow.

Upon the forming of the threads 14 on the tube, the outer end of the tube is beveled, as at 15, and this beveled end is then slightly flanged in, as at 16. A plug 17 having a tapered end 18, is slidably mounted within the tube. The diameter of the plug is slightly less than the interior diameter of the tube to provide a loose fit, so that the seepage of oil around the plug will be permitted. The tapered end 18 of the plug rests upon the flanged end 16 of the tube, so that downward movement of the plug is limited. An imperfect seat is formed between the plug and the flanged end 16 to permit the slight flow of oil between the plug and the flange, and machining of the flanged end 16 and the tapered end of the plug is eliminated. The oil seeping around the plug will follow the tapered end 18 and fall from said end drop by drop.

In order to supply oil to the bearing in accordance with the needs thereof, we provide a so-

called thermo-dome 19. This thermo-dome 19 can take the form of an elongated metal cap including an inner wall 20 and a cylindrical side wall 21 having oil inlets 22 adjacent to its outer end. The outer end of the cap beyond the oil inlets 22, is slightly reduced in diameter to provide a shoulder 23, which is adapted to abut against the flanged inner end 13 of the oil feed tube 11. The outer restricted end of the thermo-dome is forced into the inner end of the feed tube 11 and has a tight friction fit therewith.

In use of our improved lubricator, the cap 8 is removed from the reservoir 5 and the reservoir is filled with oil, and when the cap is again fitted on the neck, the reservoir is turned to its inverted position.

The threaded end of the guide sleeve can now be threaded into a bearing opening. Where the bearing opening is too large to directly receive the threaded end of the tube 11, an adapter 25 can be utilized. This adapter 25 includes an elongated sleeve 26 having its inner end split at spaced points, as at 27, to provide friction tongues 28 for engaging and gripping the sleeve. The outer end of the body 26 is provided with external threads 29 for fitting in the bearing opening 30 of a bearing 31 for a shaft 32.

When the reservoir is inverted, the oil will flow into the thermo-dome 19 and into the tube 11 above the plug 17, and will confine a body of air within the dome and slightly compress the body of air.

Normally, the oil will be held in the tube and against flow by its own capillary attraction, or by the adhesion of the oil molecules. As the bearing heats up, the heat will be conducted up the tube 11 to the thermo-dome and heat the air within the dome 19. Upon the expansion of the air, due to the raising of the temperature thereof, the oil will be forced down past the plug, and will be delivered drop-by drop to the bearing. As the bearing cools, and the air in the dome contracts, a slight suction will be placed on the oil in the tube, and hence the oil will be drawn up from around the plug.

Great stress is laid on the position of the thermo-dome 19, in that the same is entirely surrounded by the oil, which acts as a heat insulator therefor to prevent the same from being affected by an outside temperature.

If the air 24 above the oil in the reservoir expands slightly, due to room temperatures and the like, when the bearing is in a cool condition, the air in the thermo-dome, due to its compressibility, will allow the oil to rise in said dome, and thus act as a compensator or balancing means for preventing the discharge of oil to the bearing.

Changes in details may be made without departing from the spirit or the scope of this invention, but what we claim as new is:

1. The combination with a bearing, of a lubricating device therefor including a reservoir for the lubricant, and means for feeding the lubricant to the bearing from the reservoir in accordance with the temperature variation of the bearing including a thermo-dome for confining trapped air disposed wholly within the reservoir, said dome having no contact with the side and top walls of said reservoir.

2. The combination with a bearing, of a lubricating device therefor including a reservoir for the lubricant, and means for feeding the lubricant to the bearing from the reservoir in accordance with the temperature variation of the bearing including a thermo-dome for confining trapped air affected by heat from the bearing and insulated from the walls of the reservoir by the oil in said reservoir, said dome having no contact with the side top walls of said reservoir.

3. A thermo lubricating device for bearings comprising an oil reservoir, a feed tube communicating with said reservoir, and means for feeding the lubricant through the tube in accordance with the temperature variations of a bearing including a thermo-dome having a closed inner end and an open outer end fitted in the tube, said dome having oil inlets communicating with the reservoir inward of the closed end of said dome, whereby to form an air space in the dome between the oil and the closed end of the dome, said dome being wholly positioned within the oil in the reservoir having no contact with the walls thereof.

4. A thermo lubricating device for bearings comprising a reservoir including a body having one end open, a cap detachably associated with the body for sealing said open end, a feed tube connected with the cap and communicating with the interior of the body, means for restricting the flow of oil from the tube, and means for feeding the lubricant through the tube in accordance with the temperature variation of the bearing with which the tube is associated, including a thermo-dome having a closed inner end and an open outer end fitted within said tube, said dome having oil inlets adjacent to the tube and spaced from the closed inner end of the tube to form an air space between the closed inner end of the dome and the oil in said dome, the dome being wholly spaced from the side walls of the body and entirely surrounded by the oil therein, and having no contact with said walls.
